THEODORE DOUGLAS.

BY *William F. Kiekel*
ATTORNEY

UNITED STATES PATENT OFFICE.

THEODORE DOUGLAS, OF SCARBORO, NEW YORK, ASSIGNOR TO DUPLEX ENGINE GOVERNOR COMPANY, INC., OF BROOKLYN, NEW YORK, A CORPORATION OF NEW YORK.

VALVE.

Application filed April 17, 1919. Serial No. 290,666.

To all whom it may concern:

Be it known that I, THEODORE DOUGLAS, a citizen of the United States, residing in Scarboro, in the county of Westchester and State of New York, have invented certain new and useful Improvements in Valves, of which the following is a specification.

I have invented an improvement in regulating valves and operating means therefor; particularly a valve designed to be utilized in connection with internal combustion engines and other prime movers for the purpose of responding to the action of a governor and throttling the motive agent when the limiting speed of the engine is reached, and cutting off the motive agent as soon as this limiting speed is exceeded.

The primary object of my invention is to provide a valve which is simple in construction and embraces relatively few parts, and of which the movable elements require to be actuated through only a very small distance to be caused to travel from full open position to full closed position and vice versa; whereby, after the limiting speed is once reached, a very small increase in the speed of operation will cause the valve to be closed entirely, and a very small decrease below the limiting speed will cause the valve to return to full open position; thus enabling the engine to be controlled in a quick and accurate manner by the governor as the latter acts in accordance with changes in engine speed.

A further object of my invention is to provide a valve which comprises a number of relatively movable parts or elements, all of which are connected together so as to operate in unison, and which require to be moved through only a short distance; in order to stop the flow of motive agent through the supply conduit to the engine; or, after thus cutting off the motive agent, to restore free communication between the engine and the source from which said motive agent is derived.

Another object of my invention is to provide a valve comprising shutter elements which not only throttle but also give a very advantageous mixing action.

The above and other objects of my invention will clearly appear in the following

description, taken in connection with the accompanying drawings forming part of the same; and the characteristics of my invention will be precisely defined in the appended claims. I do not wish to be limited, however, to the exact embodiment herein shown, but I reserve the right to make changes in the structure by which my invention is practiced, especially as regards the shape, size and arrangement of the parts of the same, within the scope and spirit of my invention, consistent with the general meanings of the terms in which the claims are expressed, and as indicated by variations in the wording of the same.

On the drawings:—

Figure 1 is a longitudinal section through a construction made according to my invention;

Figure 2 is a top plan of a part of what is shown in Figure 1, illustrating the elements composing the valve;

Figure 3 presents a detail of what is shown in Figure 1; and

Figure 4 is an outside end view of what is shown in Figure 1.

The same numerals identify the same parts throughout.

In the particular description of the construction shown in the drawings, I show at 1 a housing for my improved valve and the means for operating same. This housing is preferably made in two sections; one of which, indicated by the numeral 2, has a passage 3 through it, and is provided with a valve 4; preferably mounted at one end of this passage. The valve 4 is made up of a number of elements arranged parallel with one another, and it is moved to open or closed position by a governor 5 arranged in the other section 6 of the housing 1, which is bolted or otherwise secured to the section 2. The section 2 is arranged to be inserted in the line of a conduit, such as the intake pipe of an internal combustion engine; and the governor 5 comprises centrifugally actuated weights, driven in accordance with the speed of the engine, to throttle the motive agent flowing through the conduit 3, when the engine reaches its limiting speed, and to cut off this motive agent as soon as the limiting speed is exceeded. To enable

the housing 1 to be supported in operative position both ends of the casing 2 will be flanged or otherwise shaped to permit adjacent ends of sections of the intake conduit to be bolted or otherwise fastened to same.

One end such as the upper end of section 2 is counterbored to provide a shoulder 7; against which fits a ring 8 in which the valve 4 is supported. This ring 8 will have a flange 9 to engage a shoulder 10 provided in the adjacent end of the section 2, and it will be secured in place by screws or other suitable fastening means. The opening 11 through the ring 8 is indicated by the numeral 11 and this opening has such an outline, that it can be controlled by a number of parallel elements 12 which have the form of shutters and constitute the valve 4. The elements 12 are fixed to spindles or shafts 13, which are pivotally mounted in the ring 8; or these elements may have trunnions at their ends which also pivotally engage the ring 8; and each element 12 will have a pair of rigid arms 14 adjacent the middle of same. The arms 14 on each element are joined by a pin 15; and all the pins 15 are connected by a link 16, pivotally engaging the pins, and disposed between the arms 14 of each element 12; and through the link the arms 14 can be actuated and the elements 12 moved.

As shown in Figure 1, each of the shutter elements 12, has its opposite faces parallel, because each of them is shaped somewhat like a parallelogram or rhombus in cross-section. That is, the elements contract towards their sides, because the opposite faces converge towards the lateral edges of the elements 12. Owing to the shape and arrangement of these elements, the passages through the valve first contract, and then expand, both when the valve is in full open position and for every other position except closed position. In other words, the passage between any two elements 12 resembles to some extent, a Venturi tube, the function and purpose of which I shall mention again later.

Adjacent the opposite end of the passage 3 I mount a transverse spindle 17 which serves as a journal for a hub 18. This spindle engages the opposite sides of the section 2; being mounted in bosses or bearings 19 and held against endwise displacement in any suitable manner. The hub 18 is rigid with a pair of parallel operating arms 20 connected at their outer ends by a transverse brace 21. These outer ends are notched and engage one of the pins 15, the arms 14 bearing this pin being received between the notched ends of the arms 20, as indicated in Figure 3. Nearer to the spindle 17, these arms 20 are also connected by a stud or the like 22 which is engaged by a notched head 23. The latter is in the form of a split nut,

adjustably mounted on an actuating element or rod 24, which is adapted to be reciprocated by the governor; and whenever the governor exerts sufficient thrust against element 24, the valve is closed. The element 24 engages screw-threads in the nut 23, which is pinched after splitting, to make it grip the rod 24; and extends across the passage 3; and between the nut 23 and one side of the passage is a coiled spring 25 encircling the element 24 and engaging both the section 2 and the nut 23; and acting to oppose the action of the governor 5 on the element 24. This spring tends to hold the valve in open position, and must be overcome by the governor before the valve can be moved.

At the point where the spring 25 is located, the section 2 has an external boss 26. This boss is open at its outer end and has a relatively large threaded bore; and the inner end of this bore communicates through a suitable aperture with the passage 3. The aperture in question is in line with the element 24, which projects therethrough into the bore of the boss 26, and terminates in a kerfed head 27. I use a recessed nut 28 to engage the boss 26 and close the same, and this nut has an aperture to register with a recess 29 in the edge of the boss; so that a locking member may engage both the aperture in the nut 28 and the recess 29, and fasten the nut 28 in closing position. Any kind of suitable locking member 30 may be employed; and whenever the locking member is removed, the nut 28 can be unscrewed and the kerfed head 27 engaged by a tool to adjust the element 24 in the head 23. If desired the element 24 may be reduced or grooved just behind the head 24, to enable it to be engaged by a tool held in the hand, and pulled to try the force of the spring 25.

The governor is actuated by a rotatable shaft 31, in line with the rod 24, and mounted in a suitable bearing 32 in the side of the section 2. The bearing in question is lined as at 33, and a washer 34 in this bearing encircles the rod 24 to prevent leakage between the sections 2 and 6. The shaft 31 is hollow and one end of the same abuts this packing. It contains a member 35 of considerable mass, and the rod 24 projects through the washer 34 into the shaft 31 so as to engage one end of this member. The opposite end of this member is arranged in proximity to a pair of longitudinal slots in the opposite sides of the shaft 31, and through these slots projects a bolt or the like 37 carried by a sliding head 38 mounted on shaft 31. Near the opposite end of the shaft 31 is a similar head 39, fixed to the shaft and held against movement; and the two heads 38 and 39 are connected by links to the governor weights and separated by an intervening spring 40, which normally acts

against the sliding head 38 to bring the links into alignment and hold the governor weights as close to the shaft as possible. The opposite end of the shaft 35 is mounted 5 in a bearing provided by a boss 41 in the section 6, which also is provided with a lining 33.

The mode of operation of the construction thus far described, will now be apparent. 10 Whenever the engine reaches its limiting speed the rotation of the shaft 31, through the centrifugal action of the governor weights, draws the head 38 towards the head 39; compressing the spring 40. Thus a 15 thrust is exerted through the pin 37 on the member 35, pushing against the rod 24 to move the arms 20 to the left, as shown in Figure 1, and turn the elements 12 toward closed position. The valve 4 will be entirely 20 closed as soon as the limiting speed is exceeded. Normally there will be a slight space between the member 35 and the pin 37, and this member, besides having considerable mass will have frictional engagement 25 with the inside of the shaft 31. This construction serves to absorb jars and shocks and prevents erratic movements of the governor from actuating the valve. Hence the governor responds only to speed factors and 30 is rendered immune from vibrations and jolting; and the valve 12 is enabled to be moved only as required.

The section 2 also carries a device such as a screw plug 42, which is adjustable, and 35 abuts one end of the link 16. The opposite end of the link 16 has a projection which is received by one end of a spiral spring 43. This spring is located in a recess in the bottom of the member 8 and protrudes into another aperture through the side of section 2. 40 At its opposite end the spring engages a projection on a nut 44. Obviously by turning the plug 42 the full open position of the valve can be adjusted, and by turning 45 the nut 44 the tension of the spring 43 can be regulated.

Section 6 is also provided with an extension 45 fixed in a seat in the outer end of the boss 41. The end of the shaft 31 in this 50 boss has its bore made polygonal in cross-section to receive the correspondingly shaped end of a drive shaft 46. The extension 45 carries a washer 47 fitting against a shoulder in this extension, and surrounding the shaft 46; and this shaft, which may be a flexible shaft or any other kind of shaft, is disposed in a suitable tubular casing 48. This casing is encircled by a bushing 49, which fits the casing snugly and abuts the 55 extension 45. This bushing is encircled by a sleeve 50 which is conical on its inside, and is provided with screw-threads to enable it to be joined to the extension 45. As shown in Figure 1, when the sleeve 50 is turned up, 60 it draws one end of the bushing 49 tightly

against the extension by engaging the opposite end of the bushing; and thus holds the casing 48 rigidly to the section 6. A fastening screw 51 in the sleeve 50 may engage the casing 48 and this screw may have 70 a head through which passes a ring 52 encircling sleeve 50. The ring may have a cam member 53 to engage the sleeve 50 and draw the ring tight.

By adjusting the element 24 with reference to the head 23, the speed at which the member 35 will thrust against the rod 24, can be varied at will, and by adjusting the nut 44 the spring 43 can be regulated. This 75 spring insures a quick return of the valve to open position as soon as the speed of the engine is reduced. By manipulating the rod 24 with a tool and by turning the nut 44 or the screw 42 all the necessary adjustments can be obtained.

The shape of the elements 12 above referred to gives a Venturi-tube effect, and makes the valve not only throttle the motive agent flowing through the passage 3 but also gives a good mixing action, distributing 80 gasoline particles more evenly through the mixture; whereby the fuel is rendered very uniform. My valve thus not only serves to throttle and govern the engine, but also enables it to run more advantageously during 85 normal operation; and proper combustion and higher efficiency are secured.

An oil hole is provided at the top of section 6 and a drain hole at the bottom; with 90 removable screw plugs to fit the same.

The arms 20 may converge or be bent towards each other at their notched ends if desired to receive the two arms 14 of one element 12 snugly between them.

Having described my invention, what I 105 believe to be new and desire to secure and protect by Letters Patent of the United States is:—

1. A valve embracing a plurality of movable elements arranged side by side to provide parallel passages, said passages expanding and then contracting to give a Venturi-tube effect for all positions of the valve except closed position.

2. A valve comprising a plurality of pivoted shutter elements arranged side by side to provide parallel passages, said passages contracting and then expanding to give a Venturi-tube effect for all positions of the valve except closed position.

3. A valve comprising a plurality of shutter elements having their opposite faces parallel and contracting in thickness towards their lateral edges.

4. A valve comprising a plurality of parallel shutter elements, a pair of arms connected to each, pins joining said arms, a link pivotally connected to said pins, a notched arm engaging said link, and an element for actuating said notched arm.

5. In a valve construction, a hub, a pair of parallel arms thereon and rigid therewith, said arms having notched ends, and a transverse brace and a stud connecting said arms.

6. The combination of a valve comprising a plurality of shutter elements, a link connecting said elements, an adjustable spring abutting one end of said link, and an adjustable device for engaging the opposite end of said link.

7. A valve comprising pivotally mounted, parallel shutter elements, arms thereon, a link connecting the arms, an adjustable stop at one end of the link, an adjustable spring engaging the opposite end of said link, an arm for operating the link and an element for actuating said last-named arm.

8. A valve comprising a plurality of pivoted, parallel shutter elements, said ele-

ments having faces converging towards each side to give a Venturi-tube effect.

9. A valve comprising a plurality of parallel, pivoted shutter elements having faces converging towards each side to give a Venturi-tube effect, a pair of arms on each element, a pin joining the arms of each element, a link between the arms of each element and connecting said elements together, a pair of notched arms receiving the arms of one shutter element between them and engaging the pin thereof, a head having a notch between said operating arms, a stud extending between said operating arms to engage the head, and an element to engage the head to actuate the latter.

In witness whereof, I have signed my name to this specification this 27th day of February, 1919.

THEODORE DOUGLAS.
